LUTHER M. SIMS, OF LINCOLN, ILLINOIS.

Letters Patent No. 70,907, dated November 12, 1867.

IMPROVEMENT IN MAIL-BAGS.

The Schedule referred to in these Letters Patent and making part of the same.

TO ALL WHOM IT MAY CONCERN:

Be it known that I, LUTHER M. SIMS, of Lincoln, in the county of Logan, and in the State of Illinois, have invented certain new and useful Improvements in Locking Mail-Bag; and do hereby declare that the following is a full, clear, and exact description thereof, reference being had to the accompanying drawings, and to the letters of reference marked thereon.

In the annexed drawings, making part of this specification, A represents a mail-bag, which is constructed generally very similarly to those in common use. A flap, a, covers the opening or mouth of the bag. This flap tapers, as seen in red lines, toward its end, and has upon its end an iron or metal hasp. C represents a metallic case or box, which has its edges riveted to the bag on that side over which the flap turns. This case is sufficiently raised from the side of the bag, when secured in its place, that the flap a can pass under it between it and the bag. The case C is made in the shape of the flap a, and has at its lower end an orifice through which the hasp B passes to catch over the staple E. D represents the handle of the bag, which is secured to the flap a. The case C gives ample protection to the mouth of the bag and the flap a.

By this arrangement, mail-bags can be opened and closed much more expeditiously than they can by the plan now in use. The case C, I propose to cast of brass, so that it will not break or bend easily.

Having thus described my invention, what I claim as new, and desire to secure by Letters Patent, is—

The case C, constructed and used with the bag and its flap a, substantially in the manner and for the purpose set forth.

In testimony that I claim the foregoing invention, I have hereunto set my hand this 6th day of September, 1867.

LUTHER M. SIMS.
